RADIO TUNING DEVICE

William H. Murray, Central Valley, Calif.

Application May 22, 1939, Serial No. 275,097

5 Claims. (Cl. 250—20)

This invention relates to radio tuning devices and more particularly to an automatic time controlled device for use in combination with a radio receiver having automatic station selecting means 5 associated therewith.

An object of this invention is to provide a time controlled means in combination with a push button tuning device incorporated in a radio for automatically tuning the radio receiver to a selected 10 station at a predetermined time.

Another object of this invention is to provide an electrically operated radio tuning actuator and means controlling operation of the actuator at a predetermined time.

15 A further object of this invention is to provide a radio tuning means of this kind which is so constructed that one portion of the device may be operatively connected to the radio set and another portion of the device may be disposed 20 remote from the radio set for controlling the operation of the radio set from a remote point and at a particular time in order that a particular radio station may be tuned in by the radio receiver at a predetermined time.

25 A still further object of this invention is to provide a time controlled and electrically operated tuning means in combination with an automatically operated radio tuning control, the device being so constructed that any desired number of 30 radio stations may be tuned in at intervals selected by the user of the device, the intervals being co-ordinated with the beginning of the broadcast of the selected radio stations.

A further object of this invention is to provide 35 in a device of this kind an automatically operable time controlled tuning means including a solenoid operated circuit making and breaking means and also solenoid operated circuit breaking means associated with the first circuit making and breaking means so as to prevent oscillation of the first 40 circuit making and breaking means.

Another object of this invention is to provide in 45 a device of this kind a controlling switch whereby the device may be readily cut off in order to permit manual operation of the radio apparatus.

To the foregoing objects and to others which may hereinafter appear, the invention consists of the novel construction, combination and arrangement of parts as will be more specifically referred 50 to and illustrated in the accompanying drawings, wherein is shown an embodiment of the invention, but it is to be understood that changes, variations and modifications may be resorted to which fall within the scope of the invention as claimed.

55 In the drawings:

Figure 1 is a vertical section of a radio tuning device constructed according to an embodiment of this invention mounted on a radio shown in fragmentary side elevation.

Figure 2 is a vertical section of the control 5 means for the operator shown in Figure 1.

Figure 3 is a sectional view taken on line 3—3 of Figure 2.

Figure 4 is a diagrammatic view of the electric 10 circuits embodied in this invention.

Figure 5 is a fragmentary vertical section partly in detail taken on line 5—5 of Figure 3.

Figure 6 is a vertical section partly in detail taken on line 6—6 of Figure 3.

Figure 7 is a fragmentary side elevation of the 15 structure shown in Figure 2.

Figure 8 is a fragmentary sectional view on an enlarged scale taken on the line 8—8 of Figure 3.

Figure 9 is a longitudinal section taken through 20 a modified form of this invention.

Figure 10 is a fragmentary plan view of the circuit closing means embodied in the structure shown in Figure 9, and

Figure 11 is a vertical section through the drive 25 means incorporated at one end of the structure shown in Figure 9.

Referring to the drawings, the numeral 15 designates generally a radio cabinet including a push button or lever operated tuning means 16. The tuning means 16 at present forms a part of 30 the radio apparatus 15 and in the present instance, the tuning means 16 is constructed in the form of a push button although if desired, the tuning member 16 may be a pivoted or slidable tuning means. A housing 17 is mounted in face 35 abutting relation to the front of the cabinet 15 and comprises a front wall 18, a rear wall 19 provided with an opening 20 through which the tuning operator 16 is adapted to project. A top wall 21 is secured to the side walls 18 and 19 and the 40 end walls 22 and a bottom wall 23 is secured to the lower ends of the front and rear walls 18 and 19 and the end walls 22.

A plunger or slide member 24 is slidable in a bearing or cylindrical bushing 25 secured to the 45 front wall 18 and is provided at its forward end with a head 26 disposed in confronting relation to the button or tuning operator 16. A lever or plunger operator 27 is rockably mounted on a shaft 28 carried by the housing 17 and is provided 50 with an elongated slot 29 through which a pin 30 engaging through a slot 31 in the plunger 24 is adapted to engage. The pin 30 engages against one end of a spring 32 positioned about the plunger 24 and the opposite end of the spring engages 55

- against the head 28. A solenoid coil 33 is secured in depending relation to the top wall 21 of the housing 17 and a movable core or armature 34 engages within the coil 33 and is provided at its 5 lower end with a head 35. The core 34 is adapted to gravitationally move downwardly to an inoperative position. The lever or arm 27 is provided with an angularly disposed arm or extension 36 which extends downwardly from the shaft 10 28 and the extension 36 is connected to the solenoid 34 by a link 37. The link 37 is pivotally connected as at 38 to the lower end of the arm or extension 36 and pivotally mounted as at 39 in a slot 40 provided in the lower side of the head 35. 15 In this manner when the core 34 is drawn upwardly by the solenoid coil 33, the plunger 34 is moved forwardly and to the left as viewed in Figure 1 for engagement with the tuning operator 16. The operator hereinabove described which is 20 mounted in the housing 17 and engageable with the tuning button 16 is adapted to be electrically connected to a time controlled tuning device shown in Figures 2 to 8 inclusive, the operator being interposed in the electric circuits shown in 25 Figure 4, to be hereinafter described.
- The tuning operator 17 shown in Figure 1 is electrically connected with a selective and time controlled tuning device generally designated as 41 which comprises a cylindrical stationary housing 42 mounted on a base 43. The housing 41 is provided with a top wall 44 which is secured to the upper end of the cylindrical member 42. The cylindrical wall 42 is provided with a plurality of circumferentially spaced apart openings 45 which 30 are arranged in a plurality of vertically spaced apart series 45a, 45b, 45c, 45d, 45e and 45f, the number of rows of openings 45 corresponding to the number of buttons carried by the radio apparatus 15. The wall 42 on the inner side thereof 35 is provided with a circular band 46 for each series of openings 45 and each band 46 is provided with openings 47 registering with the openings 45. A pair of yieldable clips or clamping members 48 are secured to the inner surface or side of the band 46 and a metallic key or pin 49 is adapted to 40 be inserted through the openings 45 and 48 and is provided at its inner end with a groove or clip engaging portion 50 which is positioned outwardly from a rounded head or contact 51 carried by the inner end of the pin 49. The outer end of the pin 49 is provided with a button or knob 52 preferably, of insulated material so that the key or pin can be handled without shocking the person handling the key. 45
- Each row of openings 45 has a band 46 associated therewith and clips or holding members 48 mounted on the inner side thereof for engagement with a key 49. The holes 45 are arranged in such a manner that the space between each 50 pair of holes is equivalent to a predetermined time and in the present instance, this time is fifteen minutes, being a period of time during which certain radio broadcasting stations are operating on a particular broadcast. A cylindrical member 53 is disposed interiorly of the housing 41 and is provided with an upper wall 54, the cylindrical member 53 and the wall 54 being formed of insulating material. A vertically disposed shaft 55 is 55 rotatably mounted at its lower end in a bearing 56 carried by the base 43 and a second shaft or extension 57 is coupled to the upper end of the lower shaft 55 by an insulated coupling member 58. The shaft extension 57 is provided with threads 59 and nuts 60 and 61 are threaded onto 60 the threads 59 and engage the top wall 54 of the

cylindrical member 53 so as to tightly secure the cylindrical member 53 to the shaft member 57 for rotation thereby.

A worm gear 62 is secured to the upper end of the shaft member 57 and a worm 63 operated by a clock mechanism 64 engages the worm gear 62 so as to rotate the cylindrical member 53. The clock mechanism 64 is preferably an electrically operated clock mechanism mounted in the housing 65 carried by the upper wall 44 of the housing 10 62 and an opening 66 is provided in the central portion of the wall 44 through which the shaft 57 projects.

A vertically disposed circuit closing bar 67 is secured as by fastening members 68 to the outer side of the cylindrical member or drum 53 and is adapted upon rotation of the drum 53 to contact with a key or pin 49 in a selected opening 45. An extension 69 is connected at one end to one end of the wiper or circuit closing bar 67 and the opposite end of the extension 69 is provided with a downturned portion 70 secured as by fastening means 71 to the lower shaft 55. The bearing 56 for the shaft 55 is provided with an extension 72 and a terminal 73 is connected to the extension 72 so that a wire connected to the terminal 72 will close a circuit as will be hereinafter described upon engagement of the wiper or movable contact bar 67 with a selected key 49.

A cylindrical upwardly extending and transparent member 74 having a bottom wall 75 is mounted on the upper wall 54 of the drum 53—54 and the bottom wall 75 is interposed between the upper wall 54 and the upper nut 61 so that the cup-shaped member formed by the wall 74 and 35 the bottom 75 will rotate with the circuit closing drum 53—54. The periphery of the cylindrical part 74 is provided with graduations and time indicating means and a pilot light 76 mounted in a socket 77 carried by the bracket 78 is supported interiorly of the cylindrical member 74. The outer wall 42 of the housing 41 is provided with a window 79 through which the graduations on the drum 74—75 are visible. The graduations on the drum 74—75 are co-ordinated with the 40 clock 65 so that when a selected key 49 is mounted in a selected opening 45 a circuit will be closed at a selected time. The bracket 78 is secured by a fastening means 80 to the housing 41 and in the present instance, is secured to the cylindrical 45 wall 42.

An insulated base member 81 is mounted on the base 43 within the housing 41 and a pair of L-shaped brackets 82 are secured as by fastening means 83 to the base member 81. A rock shaft 84 is rockably mounted in the upstanding legs 85 of the L-shaped members 82 and a bar or lever 86 is secured to the rock shaft 84. The base 81 has secured to one side thereof a spring contact clip 87 and the lever or bar 86 has movably 60 mounted thereon a circuit closing pin 88. The circuit closing pin 88 is slidable through the lever or bar 86 and is provided with a shoulder 89 limiting the movement in an upward direction of the pin 88 relative to the bar 86. A spring 90 is disposed about the pin 88 above the lever 86 and at one end engages against the lever 86 and at the other end engages against a shoulder or collar 91 carried by the pin 88 at its upper end so as to constantly maintain the shoulder 89 in engagement with the under side of the lever 86.

A solenoid coil 92 is supported by a bracket 93 secured as by fastening means 94 to the base 81 and a movable core 95 having a lower head 96 is movable interiorly of the coil 92. The head 75

96 is connected to the rock lever 86 by means of a pivoted link 97 so that vertical movement of the core 96 will rock the lever 86 so as to thereby move the pin or circuit closing member 88 relative 5 to the clip 87.

A second clip 98 similar to the clip 87 is secured to the base 81 on the opposite side of the rock shaft and the second circuit closing pin or member 99 is slidably mounted in the opposite end of 10 the rock lever 86. The pin 99 has a shoulder 100 below the lever 86 so as to limit the upward movement of the pin 99 relative to the lever 86. A spring 101 is disposed about the pin 99 on the upper side of the lever 86 and the upper end 15 of the spring engages a shoulder 92 carried by the pin 99 at its upper end and the lower end of the spring 101 engages the upper side of the lever 86. The pin 99 is adapted to be connected to one side of an electric circuit as will be hereinafter described.

A solenoid coil 103 is mounted on a bracket or supporting member 104 secured as by fastening means 105 to the base 81 and a movable core 106 is movable relative to the coil 103. The core 106 has a head 107 at its lower end which is connected as by a pivoted link 108 to the rock lever 86. Through the use of the two solenoid coils 92 and 103 the rock lever 86 is rocked in one direction by the coil 92 and in the other direction 30 by the coil 103.

A liquid switch 109 is mounted in a clip or holder 110 carried by the rock shaft 84 and extends transversely of the rock shaft 84. This liquid switch 109 is adapted to be interposed in an electric circuit which is opened and closed by rocking of the shaft 84 and the lever 86 under the action 35 of the movable core members 95 and 106. In this manner movement of the lever 86 in one direction will operate to break an electric circuit 40 through the liquid switch 109 and movement of the rock lever 86 in the opposite direction will act to close the electric circuit associated with the switch 109. The lever 86 is provided on its under side with a depending member 127 and a yieldable 45 lever holding member 128 is secured to the base 81 and is engaged with the depending member 127 so as to yieldably hold the lever 86 in a selected position determined by operation of one of the solenoid coils 92 or 103.

50 A circuit breaking relay generally designated 111 is mounted on a base 112 secured to the base 43 within the housing 41. This circuit breaking relay 111 comprises a pair of stationary contacts 113 and 114 as having terminals 115 and 116 respectively. These contacts 113 and 114 are disposed in spaced apart relation and are adapted to be connected to electric circuits to be herein-after described. A solenoid coil 117 is supported by a bracket or supporting member 118 of substantially U-shape which is secured to the base 112. A movable core 119 is movable within the coil 117 and the core 119 has a head 120 at its lower end. A contact bridging member 121 is adapted, when in operative position, to bridge the 55 two contacts 113 and 114 and is provided with a central opening 122 through which a bar 123 slidably engages. The bar 123 at its lower end is provided with a head 124 and the upper end of the bar 123 is secured as at 125 to the head 120. A spring 126 is disposed about the bar 123 and the upper end of the spring 126 engages against the head 120 and the lower end of the spring 126 engages against the bridging member 121.

A transformer 129 is mounted on the base 43 75 within the housing 41 and the primary of the

transformer 129 is adapted to be connected to a source of electric current supply. The secondary of the transformer 129 is adapted to be connected to the solenoids hereinbefore described.

The transformer 129 has the primary coil 5 thereof connected as by conductors 130 and 131 to a source of electric current supply. The clock mechanism 64 is connected as by conductors 132 and 133 to the conductors 130 and 131 respectively. A pilot light 134 is interposed in the conductors 132 and 133.

The liquid switch 109 has one side thereof connected as by a conductor 135 to the conductor 131 and the other side is connected as by a conductor 136 to one side of the radio apparatus 15. 15 The other side of the radio apparatus 15 is connected by a conductor 137 to the conductor 130. The secondary 138 of the transformer 129 has a conductor 139 connected to one side thereof and a conductor 140 connected to the other side 20 thereof. The conductor 139 is connected to one side of each of the solenoid coils 92, 103, and 117 as shown in Figure 4. The conductor 140 is connected to the terminal 73 which is electrically connected to the wiper or circuit closing bar 67. 25 A conductor 141 is connected to the upper ring 46 carried by the drum 53 and is also connected to the terminal 115. The opposite side of the circuit breaking relay 111 is connected as by a conductor 142 to the conductor 141. The contact 114 is connected to the yieldable contact or clip 87 by a conductor 143 and this conductor 143 is also connected to the yieldable clip or contact 98. One side of the solenoid coil 33 of the button operating member is connected as by a conductor 144 to a ring 46a and the other side of the solenoid coil 33 is connected as by a conductor 145 to the conductors 139 on one side of the secondary coil 138. 30

A switch member 146 is secured to the housing 40 41 and includes a pair of stationary terminals 147 and 148, the terminal 147 being connected as by a conductor 149 to the conductor 136. The terminal 148 is connected to the conductor 131. The switch 146 also includes a second pair of 45 terminals 150 and 151 and a V-shaped circuit closing blade 152. The terminal 150 is connected to the conductor 131 so that when the switch 146 is in one position, the position shown in full lines in Figure 4, the long side of the blade 152 will 50 bridge the two terminals 148 and 150 to the primary 153 of the transformer 129. In the opposite position, the long blade of the switch 146 bridges the space between the two terminals 147 and 151 and the opposite or short blade 154 will 55 engage the terminal 150 so that a circuit will be completed from the conductor 131 through the conductor 149 and the terminals 147 and 150 to one side of the liquid switch 109.

In Figures 9, 10 and 11, there is disclosed a 60 slightly modified form of controlling means for the operator disclosed in Figure 1. A housing 156 is provided including upstanding end walls 157, side walls 158, a bottom wall or base and a rear wall 159. An arcuate or arched front wall 65 160 is secured to the base wall 158 and the end walls 157 and is provided with a plurality of spaced apart openings 161. The openings 161 are spaced apart in a manner similar to the openings 45 of the housing 42 and the front wall 70 160 is provided with a row of openings 161 for each tuning member 13, in addition to a separate row of openings 161 for the main circuit comprising the conductors 139 and 140 which control the movement of the liquid switch 109. The 75

front wall 160 is provided on the under side thereof with an elongated strip or band 162 for each row of holes 161 and yieldable clips 163 similar to the clips 48 are secured to each band 5 162 so as to yieldably hold a circuit closing key or pin 164 in a selected opening 161. A flexible circuit closing band 165 is disposed in the housing 156 and is trained over a pair of sprockets 166 mounted on a shaft 167 journalled in the 10 housing 156 and is also trained over sprockets 168 mounted on a shaft 169 at the opposite end of the housing 156. The shaft 169 has a worm gear 170 secured thereto with which a worm 171 meshes. The worm 171 is carried by a shaft 172 15 which is operated from a clock or motor mechanism 173 of conventional construction. The band 165 is preferably formed of metal or conductive material and is provided with a pair of key engaging strips or bars 174 and 175 which 20 are spaced apart substantially one-half the length of the band 165. The sprockets 168 are preferably insulated from the shaft 169 whereas the sprockets 166 and the shaft 167 are of conductive material and a terminal 176 is carried 25 by an end wall 157 and is electrically connected to the shaft 167 and the sprockets 166 so as to energize the band 165.

The band 165 is maintained in the desired spaced relation to the underside of the metal strips 162 by means of an arcuate or arched guide member 177 which is secured as by supporting brackets 178 to the side walls 158 of the housing 156. The housing 156 is provided on the interior thereof with a relay 178^a which is similar 30 to the relay embodied in Figure 2 comprising the solenoids 92 and 103 and the operating parts associated therewith. A circuit breaking relay or switch member 179 is also mounted in the housing 156 and is similar to the circuit breaking relay 111 and a voltage reducing transformer 180 35 similar to the transformer 129 is mounted in the housing 156. The electrical connections between the relays 178^a, 179 and the transformer 180 are similar in every detail to the diagrammatic connections shown in Figure 4.

In the use and operation of this radio apparatus tuning means the tuning operator 17 is adapted to be secured in any suitable manner to the front face of the radio receiving apparatus 15 so that the tuning members 16 will project through the opening 20 into the interior of the housing supporting the operators. A key member 49 is inserted in a selected opening 45 and snugly held by means of the clips 48 for 50 wiping engagement with the circuit closing bar 67. The key member 49 shown in contact with the bar 67 will close the lower voltage circuit from the secondary of the transformer 129 through the conductor 140, conductor 141, bridging member 121, conductor 143 and conductor 139. Upon closing of the circuit to the secondary 55 138 of the transformer 129, the electric current will flow through the solenoid coil 117, through the conductor 142 and at this time, the core 119 60 will be raised, moving the switch operating bar 123 upwardly. In view of the fact that the head 124 of the bar 123 is spaced downwardly from the bridging member 121, there will be a delay 65 in the breaking of the circuit between the two contacts 114 and 115. This delay in the breaking of the circuit between the conductor 141 and the conductor 143 will permit the electric current to flow to the solenoid 103. When the solenoid 103 is energized the core 106 will be drawn upwardly so as to disconnect the blade or pin 99 70 75

from the terminal or clip 98. The sliding connection between the pin 99 and the bar 86 will also permit a slight delay in the breaking of the electric circuit to the solenoid 103, the bar 86 moving upwardly with the movement of the core 106 and compressing the spring 101.

The circuit breaking member 111 is provided so as to prevent continued rocking of the lever 86 and alternate opening and closing of the switch 109 which would result by closing of the electric circuit to the coil 103 which raises one end of the lever 86 until the lever 86 breaks the circuit to the coil 103. At this time the switch 109 is closed and the opposite end of the lever 86 has closed a circuit through the clip 87 and pin 90 15 to the coil 92. At this time also the circuit breaker 111 has broken the circuit from the wire 141 to the wire 143 and this circuit will remain broken so long as current flows from wires 141 and 142 to the coil 117 and the wire 139, so that 20 even though the coil 92 is connected through the switch comprising the pin 90 and the clip 87 and coil 92 is not energized because the switch comprising the terminals 114 and 115 and bridging member 121 is open. 25

Rocking of the bar 86 under the upward movement of the core 106 will cause the liquid switch 109 to be rocked to a circuit closing position, closing the electric circuit from the primary 153 of the transformer 129 through the conductors 30 135 and 136 and the conductor 137 to the radio apparatus. Closing of the liquid switch 109 will effect a closing of the main operating circuit to the radio apparatus 15 so as to energize the radio apparatus. 35

At the same time that the circuit closing bar 67 engages the key 49, the bar 67 will engage a selected key 49a which closes a circuit through the conductor 144 and the conductor 145 to the solenoid 33. When the solenoid 33 is energized, 40 the core 34 will be drawn upwardly and movement of this core 34 upwardly will effect forward movement of the plunger 24. The head 26 of the plunger 24 will then engage the tuning member 16 and effect movement thereof so as to thereby 45 tune a selected broadcast band in the radio apparatus 15. The forward movement of the plunger 24 is cushioned by the spring 32.

A tuning device constructed according to this invention may be partly connected directly to 50 the radio apparatus and another part disposed remote from and connected to the first part for controlling operation of the radio apparatus under a time controlled means. It will, of course, be understood that if desired the time controlled 55 means may be directly incorporated in the radio cabinet or apparatus, but primarily the device is constructed as an attachment for connection to the present structure of radio apparatus provided with selective station tuning devices. The 60 time controlled tuning means hereinabove described may be either cut on or off by operation of the manually operable switch 146 which is connected to the transformer 129 and also to the liquid switch 109. If it is desired to manually 65 control the radio apparatus the switch 146 will be positioned as shown in full lines in Figure 4.

However, if it is not desired to control the radio apparatus by the hereinbefore described 70 time controlling means, the switch 146 is moved to the dotted line position shown in Figure 4 wherein the blade 152 bridges the two terminals 147 and 151 and the blade 154 bridges the terminals 150 and 151. 75

The radio receiving apparatus 15 may be cut off at a predetermined time by inserting a second key 49 in a succeeding opening 45 so that when the clock mechanism 65 rotates the drum 53, the bar 67 will contact the second key 49 and thus close the circuit through the conductors 139, 140, 141 and 143 to the solenoid coils 117, 92 and 103. While the radio apparatus is in operation the switch 109 is closed and the pin 10 90 is in contact with the terminal 81. Upon closing of the circuit by the succeeding pin 49, the solenoid coil 92 will be energized so as to move the pin 93 to a released position, thus moving the bar 86 to a position whereby the 15 switch 109 will be in a circuit breaking position. In this manner the radio apparatus 15 may be cut off at any predetermined time and if it is desired to turn the radio apparatus on again at a succeeding time, an additional pin or key 20 49 may be inserted in a further succeeding opening or socket 45.

What I claim is:

1. An attachment for a radio receiving apparatus having selective tuning members, an electro-magnetic operating member for each tuning member, circuit closing means for said operating member, a switch connected to the supply source for the radio apparatus and connected to the radio apparatus, a switch operating circuit, an electro-magnetic operator connected to said switch for moving said switch to a circuit closing position, a second electro-magnetic operator connected to said switch for moving said switch to a circuit breaking position, a single electric circuit for said electro-magnetic operators, a circuit making and breaking means in said latter circuit and connected to said operators for operation thereby, said circuit making and breaking means including means whereby energization of one of said operators will break the electric circuit thereto, and simultaneously close the circuit to the other operator, a relay in said single circuit for breaking said circuit upon energization of one of said operators, and means for energizing said first electro-magnetic operating member. 45
2. An attachment for a radio receiving apparatus having selective tuning members, an electro-magnetic operating member for each tuning member, circuit closing means for said operating member, a switch connected to the supply source for the radio apparatus and connected to the radio apparatus, a switch operating circuit, an electro-magnetic operator connected to said switch for moving said switch to a circuit closing position, a second electro-magnetic operator connected to said switch for moving said switch to a circuit breaking position, a single electric circuit for said electro-magnetic operators, a circuit making and breaking means in said latter circuit and connected to said operators for operation thereby, said circuit making and breaking means including means whereby energization of one of said operators will break the electric circuit thereto, and simultaneously close the circuit to the other operator, said circuit making and breaking means also including a pair of loosely coupled members operable to delay the breaking of the circuit to an operator until the operator has substantially completed a cycle in 50 its operation, a relay in said single circuit for breaking said circuit upon energization of one of said operators, and means for energizing said first electro-magnetic operating member. 55
3. An attachment for a radio receiving apparatus having selective tuning members, an electro-magnetic operating member for each tuning member, circuit closing means for said operating member, a switch connected to the supply source for the radio apparatus and connected to the radio apparatus, a switch operating circuit, an electro-magnetic operator connected to said switch for moving said switch to a circuit closing position, a second electro-magnetic operator connected to said switch for moving said switch to a circuit breaking position, a single electric circuit for said electro-magnetic operators, a circuit making and breaking means in said latter circuit and connected to said operators for operation thereby, said circuit making and 60
4. An attachment for a radio receiving apparatus having selective tuning members, an electro-magnetic operating member for each tuning member, circuit closing means for said operating member, a switch connected to the supply source for the radio apparatus and connected to the radio apparatus, a switch operating circuit, an electro-magnetic operator connected to said switch for moving said switch to a circuit closing position, a second electro-magnetic operator connected to said switch for moving said switch to a circuit breaking position, a single electric circuit for said electro-magnetic operators, a circuit making and breaking means in said latter circuit and connected to said operators for operation thereby, said circuit making and 65
5. An attachment for a radio receiving apparatus having selective tuning members, an electro-magnetic operating member for each tuning member, circuit closing means for said operating member, a switch connected to the supply source for the radio apparatus and connected to the radio apparatus, a switch operating circuit, an electro-magnetic operator connected to said switch for moving said switch to a circuit closing position, a second electro-magnetic operator connected to said switch for moving said switch to a circuit breaking position, a single electric circuit for said electro-magnetic operators, a circuit making and breaking means in said latter circuit and connected to said operators for operation thereby, said circuit making and 70
6. An attachment for a radio receiving apparatus having selective tuning members, an electro-magnetic operating member for each tuning member, circuit closing means for said operating member, a switch connected to the supply source for the radio apparatus and connected to the radio apparatus, a switch operating circuit, an electro-magnetic operator connected to said switch for moving said switch to a circuit closing position, a second electro-magnetic operator connected to said switch for moving said switch to a circuit breaking position, a single electric circuit for said electro-magnetic operators, a circuit making and breaking means in said latter circuit and connected to said operators for operation thereby, said circuit making and 75

paratus having selective tuning members, an electro-magnetic operating member for each tuning member, circuit closing means for said operating member, a switch connected to the supply source for the radio apparatus and connected to the radio apparatus, a switch operating circuit, an electro-magnetic operator connected to said switch for moving said switch to a circuit closing position, a second electro-magnetic operator connected to said switch for moving said switch to a circuit breaking position, a single electric circuit for said electro-magnetic operators, a circuit making and breaking means in said latter circuit and connected to said operators for operation thereby, said circuit making and breaking means including means whereby energization of one of said operators will break the electric circuit thereto, and simultaneously close the circuit to the other operator, said circuit making and breaking means also including means whereby the breaking of the electric circuit to an operator is delayed until an operator has substantially completed a cycle in its operation, a relay in said single circuit for breaking said circuit upon energization of one of said operators, said relay including means for holding said single circuit closed for a period of time sufficient to permit an operator to complete a cycle of its operation, and means for energizing said first electro-magnetic operating member. 30

4. An attachment for a radio receiving apparatus having selective tuning members, an electro-magnetic operating member for each tuning member, circuit closing means for said operating member, a switch connected to the supply source for the radio apparatus and connected to the radio apparatus, a switch operating circuit, an electro-magnetic operator connected to said switch for moving said switch to a circuit closing position, a second electro-magnetic operator connected to said switch for moving said switch to a circuit breaking position, a single electric circuit for said electro-magnetic operators, a circuit making and breaking means in said latter circuit and connected to said operators for operation thereby, said circuit making and breaking means including means whereby energization of one of said operators will break the electric circuit thereto, and simultaneously close the circuit to the other operator, said circuit making and breaking means also including a pair of loosely coupled members operable to delay the breaking of the circuit to an operator until the operator has substantially completed a cycle in 40 its operation, a relay in said single circuit for breaking said circuit upon energization of one of said operators, and means for energizing said first electro-magnetic operating member. 45

5. An attachment for a radio receiving apparatus having selective tuning members, an electro-magnetic operating member for each tuning member, circuit closing means for said operating member, a switch connected to the supply source for the radio apparatus and connected to the radio apparatus, a switch operating circuit, an electro-magnetic operator connected to said switch for moving said switch to a circuit closing position, a second electro-magnetic operator connected to said switch for moving said switch to a circuit breaking position, a single electric circuit for said electro-magnetic operators, a circuit making and breaking means in said latter circuit and connected to said operators for operation thereby, said circuit making and 60

breaking means including means whereby energization of one of said operators will break the electric circuit thereto, and simultaneously close the circuit to the other operator, said circuit making and breaking means also including a pair of loosely coupled members operable to delay the breaking of the circuit to an operator until the operator has substantially completed a cycle in its operation, a relay in said single circuit for

breaking said circuit upon energization of one of said operators, said relay including a pair of loosely coupled members for holding said single circuit closed for a period of time to permit an operator to complete a cycle of its operation, and means for energizing said first electromagnetic operating member. 6
